CLAIMThe ornamental design for a fingernail gel curing lamp, as
shown and described.**DESCRIPTION**

FIG. 1 is a front perspective view of a fingernail gel curing lamp showing our new design;

FIG. 2 is a rear perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines illustrate portions of the fingernail gel
curing lamp and form no part of the claimed design.**1 Claim, 8 Drawing Sheets**| References Cited
